M. A. POSSONS

LATCH

Filed June 19, 1924

UNITED STATES PATENT OFFICE.

MINARD A. POSSONS, OF CLEVELAND, OHIO, ASSIGNOR TO AMERICAN STOVE COMPANY, OF ST. LOUIS, MISSOURI, A CORPORATION OF NEW JERSEY.

LATCH.

Application filed June 19, 1924. Serial No. 721,002.

This invention relates to improvements in latches, and pertains more particularly to a door latch designed primarily for use on stoves to latch the oven doors in their closed position.

It is essential in the building of gas and other stoves, to make the appearance of the stove as pleasing as possible. It is with this end in view that I have designed the latch hereinafter described, which is so constructed that it is held in place by the use of one bolt only and the catch itself is in the oven and, therefore, concealed when the oven doors are closed.

One object of the invention is to provide a door latch of the type described, which is concealed from view.

Another object of the invention is to provide a door latch of the type described which is very simple of construction and easy and rapid of application to a stove oven or the like.

A further object of the invention is to provide a latch of the character described, which is fastened in place by the use of one bolt only.

Another and further object of the invention is to provide a latch of the character described, which is simple of construction, cheap of manufacture and highly efficient in operation.

Other further objects, novel features of construction and advantages of my improved latch will appear in the following description and accompanying drawings.

In the drawings:—

Figure 1 is a fragmentary vertical sectional view of an oven front and doors.

Fig. 2 is an enlarged detailed vertical sectional view through my improved latch, the upper end of an oven door being shown in dotted lines.

Fig. 3 is a fragmentary front view of my improved latch.

The preferred construction and application of my latch is set forth in the accompanying drawing and the following description, in which like parts are designated by similar reference numerals, although it will be readily understood that departures can be made from the specific form shown in the invention without departing from the spirit of the invention or the scope of the claims.

I have designated an oven of a gas stove

or the like, by the numeral 1, the oven being provided with a top 2, which has a downwardly depending flange 3, around the oven door aperture. This depending flange is of double thickness, the material of the top being bent backwardly upon itself and extending under the top 2 of the oven, as at 4.

As is usual in the construction of stoves, the oven is provided with two doors, one giving entrance to the oven above the oven burner and the other door giving entrance to the oven below the oven burner. In the stove construction shown in Fig. 1, the two oven doors are separated by a plate 5, provided with an opening 6, closed by suitable transparent material 7, through which a view of the interior of the oven may be obtained.

The oven doors, shown in Fig. 1, comprise a back 8, the edges of which are bent outwardly and downwardly as at 9, upon the front panels 10 of the door to retain these panels in place. For the purpose of appearance, these panels are usually coated with enamel and carry the trade-name of the stove.

As is also common, the doors are pivotally supported upon hinges 11 and provided with operating handles 12.

Surrounding the upper oven door opening is a frame, which is L-shaped in cross-section. The horizontal leg 13 of the frame rests upon the top 2 of the oven while the vertical leg 14 of the frame extends down the front of the oven and is bent inwardly as at 15 to form a stop for the oven door by engaging the upper end 16 of the oven door back 8.

In the case of the lower door, it will be seen that the oven door stop 15 is provided by bending the lower end of the plate 5 inwardly.

As clearly appears in Figs. 1 and 2, of the drawing, the front oven panel 10 is not as large as the oven back 8, and thus the outwardly and downwardly bent ends 9 of the oven back 8 form an opening 17 around the edges of the front door panel.

My improved latch consists of a piece of spring metal having a vertical leg 18, the lower end of which is bent into U-shape 19, terminating in a forwardly extending end 20, having upwardly bent edges 21 to form a yoke in which is suitably supported a roller 22.

As will be readily seen the latch is held in place by a bolt or screw 23, which penetrates the vertical wall 14 of the frame, the vertical front flange 3 of the oven top 2 and the vertical leg 18 of the latch. The bolt 23 is provided with a nut 24. The vertical leg 18 of the latch, as clearly appears in Fig. 2 of the drawings, is positioned behind the oven front flange 3 and the vertical leg 4 of the frame surrounding the oven opening.

Due to the U-shaped bend of the latch and the forwardly extending end 20 thereof, the latch extends backwardly into the oven 1 and forwardly around the oven stop 15. When the oven door is closed, the latch end 20 and its roller 22 enter an opening 25 in the oven back 8, the roller engaging the lug 26 formed on the inner side of the upper end 16 of the oven back 8.

Due to the fact that the material of which the latch is made is light and springy, the oven door is held closed through spring tension of the roller 22 with the edge 26 of the oven back opening 25. The latch, however, will release and allow the door to swing open when a reasonable amount of pull is exerted upon the oven door handle 12.

The latch used for the lower oven door is of the same construction and the same configuration as has been just described, the latch, however, in this instance being fastened to the panel 5, which separates the oven door.

From the foregoing, it will be seen that I have provided a latch which is very simple of construction and which can be held in place by the use of only one bolt or screw. Furthermore, I have provided a latch which is entirely concealed from view when the oven door is closed as the latch is entirely within the oven. Also the member which the latch engages to hold the door closed is very simply and cheaply provided by merely cutting an opening in the back wall 8 of the oven door, thus allowing the front end of the latch and its roller to enter the opening 17 formed at the upper edge of the oven door.

Having thus described my invention what I desire to claim and secure by Letters Patent is:

1. The combination with an oven and a door therefor having a door lining provided with an opening, of a latch comprising a vertical leg having an extending horizontal end portion, said latch carried upon the inner front face of the oven, and the extending end of the latch adapted to pass through the door lining opening to engage the door and hold the door in closed position.

2. The combination with a door, of a latch comprising a vertical leg having an extending horizontal end portion, said end carry-

ing a roller for engaging the door, for the purpose described.

3. The combination with a door, of a latch comprising a piece of spring metal having a vertical leg terminating in a horizontally extending end portion, said door being provided with an opening, and the extending end of the latch adapted to extend into said door opening and engage the edge thereof, for the purpose described. 75

4. The combination with an oven and a door therefor, of a latch comprising a vertical leg having an extending horizontal end portion, said latch carried upon the inner front face of the oven, and the extending end of the latch adapted to engage the door, for the purpose described. 80

5. The combination with an oven and a door therefor having a door lining provided with an opening, of a latch comprising a vertical leg having an extending horizontal end portion and carrying a roller, said latch carried upon the inner front face of the oven, and the extending end of the latch adapted to pass through the door lining opening to engage the door and hold the door in closed position. 85 90

6. The combination with an oven and a door therefor, of a latch composed of spring metal having a vertical leg terminating in a U-shaped bend, the end of the lower wall of the U adapted to engage the door, and all of said latch with the exception of the end engaging the door lying wholly within the oven, for the purpose described. 100

7. In combination with an oven and an oven door, a latch having one end fastened to the inner front face of the oven above the door opening, and the opposite end of the latch adapted to extend outwardly 105 through the door opening and engage the door and hold it in closed position.

8. In combination with an oven and an oven door, a latch having one end fastened to the inner front face of the oven above the door opening, and the opposite end of the latch extending at right angles and provided with a roller, whereby said extending latch end and roller extend outwardly through the door opening and engage the door when the door is in a closed position. 110 115

9. The combination of an oven door and a latch therefor, the door provided at its inner side with a lug and a lining having an opening positioned in front of the lug, a latch having one end fastened to the inner face of the oven above the door, and the opposite end of the latch bent outwardly, whereby the extending latch end enters the door lining opening and engages the door lug and holds the door in closed position. 120 125

In testimony whereof I hereunto affix my signature.

MINARD A. POSSONS.
